UNITED STATES PATENT OFFICE.

CHARLES J. NELSON AND OLAF OSTLIN, OF MAYWOOD, ILLINOIS, ASSIGNEES TO AMERICAN CAN COMPANY, OF NEW YORK, N. Y., A CORPORATION OF NEW JERSEY.

STATIONARY CAN-DOUBLE-SEAMING MACHINE.

No. 923,687.

Specification of Letters Patent.

Patented June 1, 1909.

Application filed January 31, 1908. Serial No. 413,537.

To all whom it may concern:

Be it known that we, CHARLES J. NELSON and OLAF OSTLIN, citizens of the United States, residing in Maywood, in the county 5 of Cook and State of Illinois, have invented a new and useful Improvement in Stationary Can-Double-Seaming Machines, of which the following is a specification.

This invention relates to stationary can 10 double seaming machines.

The object of the invention is to provide a stationary can double seaming machine of a simple, efficient and durable construction, having a continuously rotating seaming head, carrying a plurality of seaming rollers, and in which the lower reciprocating can 15 holder or chuck may be operated by a foot lever or treadle, and the mechanism for operating or advancing the seaming rollers 20 against the can be automatically set in operation by depression of the foot lever or treadle, and in which, after the seaming operation on each can is completed, the seaming rollers or tools will be automatically 25 withdrawn from the can independent of the action of the operator's foot on the foot lever or treadle, whether it is kept too long depressed or not.

The invention further consists in the novel 30 construction of parts and devices and in the novel combinations of parts and devices herein shown and described.

In the accompanying drawing forming a part of this specification, Figure 1 is a side 35 elevation of a stationary can double seaming machine embodying the invention. Fig. 2 is a front elevation. Fig. 3 is a detail vertical section on line 3—3 of Fig. 1. Fig. 4 is a horizontal section on line 4—4 of Fig. 3. Fig. 5 is a detail vertical section on line 5—5 40 of Fig. 1. Fig. 6 is a detail plan view of a part hereinafter to be described. Fig. 7 is a detail section on line 7—7 of Fig. 11. Fig. 8 is a detail elevation, partly in vertical section, of one of the seaming roller levers. Fig. 9 is a plan view of same. Fig. 10 is a 45 detail horizontal section on line 10—10 of Fig. 1, the section line 10—10 being also indicated on Fig. 5. Fig. 11 is a detail section on line 11—11 of Fig. 5. Fig. 12 is a detail section on line 12—12 of Fig. 5. Fig. 13 is a detail cross sectional view showing the clutch. Fig. 14 is a detail end view of the parts shown in Fig. 8; Fig. 15 is a detail

perspective view of the clutch disengaging device, hereinafter described.

In the drawing, A represents the frame of the machine, B is the lower reciprocating can holder chuck and C a feed table for the cans, surrounding the chuck B. The chuck B has a shank b, fitting in a suitable socket b¹ in a reciprocating stem or rod B¹ by which the chuck B is moved up and down. The stem B¹ is furnished with a spring b² to give a yielding support to the lower can chuck. 65 The stem B¹ is operated or moved up and down as required to chuck the can against the opposing stationary or non-rotating chuck D, by means of a foot lever or treadle E operating through the sliding connecting link E¹, having a spring E² and provided with a pawl E³ adapted to engage a block or projection E⁴ on the link or slide E⁵ which is pivotally connected to the arm E⁶ of a rock shaft E⁷, having an arm E⁸ engaging a block 75 or connection E⁹ on the chuck stem B¹. The pawl E³ is furnished with a spring E¹⁰ and with a cam face E¹¹ which engages a roller E¹² on the stationary frame, and thus disengages the pawl E³ from the projection 80 E⁴ and thus permits the lower chuck B to return again to its normal position by its own gravity after the seaming operation has been completed, the operator effecting this by simply giving a slight additional impulse 85 to the foot lever or treadle E against the tension of the spring E².

F is a continuously rotating seaming head upon which the seaming rollers G G^a and seaming roller levers G¹ are mounted, and 90 by which the same are carried rapidly around the can. The seaming head F is secured to its hollow shaft or rotating sleeve F¹ by a screw threaded cap F², to which cap said head F is attached by screw bolts, as 95 shown in Fig. 11, and said sleeve is continuously driven as required by means of a bevel gear f thereon, which meshes with a bevel gear f¹ on the driving shaft K, which is furnished with fast and loose pulleys K¹ K². 100

The upper stationary can holder or chuck D is removably connected by screw threads d to a stationary stem or shaft D¹ which is secured at its upper end to the frame of the machine, and which is adapted to be adjusted up and down by means of an adjusting screw d¹.

The seaming roller levers G¹ are all in the

form of rock shafts, and are pivotally connected to the seaming head and are preferably four in number, as it is preferable to use two pair of seaming rollers,—two forming rollers G and two finishing rollers G^a, each pair being arranged diametrically opposite so that both forming rollers and both finishing rollers will engage the cans at diametrically opposite points at the same time.

10 The lower arms g of the seaming roller rock shafts G¹ are each preferably furnished with an adjustable member g¹, adjustably connected to the arm g by a connecting stud g², clamp nut g³, screw stud g⁴ which fits in the slot g⁵ in said arm g, the meeting faces of the arms g and g¹ being also furnished with interengaging devices g⁶ and g⁷. The interengaging devices g⁶ g⁷ preferably consist of a plurality of notches on the one part and a projection on the other part adapted to take into one of the notches on said first mentioned part. The adjustable member of the rock shaft arm upon which the seaming roller G is directly carried, thus enables the machine to be quickly set for operation upon cans of different diameters. Each of the rock shafts G¹ is also furnished with an upper operating arm g⁸ carrying a roller g⁹ which engages a continuously rotating cam H or H¹ by which the seaming roller is operated or advanced against the seaming flanges of the can and can cover, and maintained in position thereagainst during the seaming operation. The operating arms g⁸ which 35 actuate the two finishing rollers G^a are furnished with yielding extensions or supplemental arms g¹⁰ upon which the cam engaging rollers g⁷ are directly mounted, the two arms g⁸ and g¹⁰ being yieldingly connected together by a pivot pin g¹¹, operating in conjunction with a rubber or other spring or cushion g¹² interposed between the bent arms g¹³ on the arms g⁸ and g¹⁴ on the supplemental arm g¹⁰. This causes the finishing 40 rollers G^a to be forced and maintained against the seam with a yielding pressure, and aids materially in producing hermetically tight double seams.

45 The operating cams H and H¹, one for actuating the forming rollers G G¹, and the other for actuating the finishing rollers G^a G^a, are both secured in the required relative position to each other on the continuously rotating cam sleeve H² which surrounds the seaming head sleeve F¹, and which rotates continuously, at times with or at the same speed as the seaming head sleeve, and at other times at a differential speed, preferably a slightly faster one, so as to bring 50 the cams into action against the seaming roller rock shafts. Preferably the cam sleeve H² makes, say, thirteen revolutions to twelve revolutions of the seaming head sleeve when said cam sleeve is being independently driven by the seaming roller actuating mechanism.

55 The cam sleeve H² is furnished with a bevel gear h, which meshes with a bevel gear h¹ on the shaft h² which is furnished with a loose spur gear h³ that meshes with a spur gear h⁴ fast on the driving shaft K, the spur gears h⁴ h³ having a differential number of teeth, so that when the differential gear h³ is clutched to the shaft h², said shaft will be driven at a different speed from the shaft K, and thus cause the cam sleeve H² to rotate at a different speed from the seaming head shaft F¹, and thereby cause the cans to force the seaming rollers inward against the can, and maintain the same properly in operative relation until the seaming operation is completed.

60 The differential gear h³ is furnished with clutch pins or members h⁵, which are adapted to be engaged by the teeth of a sliding clutch h⁶ on the shaft h², and which is operated by a bent clutch lever h⁷ pivoted to the frame at h⁸, and having a spring h⁹ by which it is automatically retracted and the differential gear h³ unclutched from the shaft h² when the seaming operation for each can is completed. The lever h⁷ is connected by a link h¹⁷ with the arm E⁶ of the rock shaft E⁷.

65 The differential gear h³ is automatically clutched and unclutched from the cam sleeve operating shaft h² at the completion of each seaming operation by means of a stop cam M on the intermittently rotating shaft M¹, said cam having a notch m engaging a roller h¹⁰ on the lock-arm h¹¹ of the clutch operating lever h⁷. The shaft M¹ of the stop cam M makes one complete revolution for each seaming cycle period of operation for each can. The locking arm h¹¹ is withdrawn from the stop cam M so as to release the same and permit it to begin to rotate at the beginning of each seaming cycle or period, by operation through link h¹⁷ of the clutch lever h⁷ which moves the clutch member h⁶ into engagement with the clutch member h⁵ on the differential gear h³.

70 The stop cam M is intermittently operated as required, by means of a pulley K¹¹ on the driving shaft K and belt K¹² running on a pulley n of the worm shaft N which is furnished with a worm n¹ that meshes with a worm gear m²¹ loose on the stop cam shaft M¹ and which is furnished with a clutch member m¹ adapted to engage a sliding clutch pin or member m² on the clutch sleeve m³ which is furnished with an annular groove m⁴ to receive a curved or crescent shaped wedge or clutch disengaging device m⁵ that operates to retract the clutch pin or member m² from the clutch member m¹ at each revolution of the groove clutch sleeve m³ which is fast on the shaft M¹. The sliding clutch pin or member m² has a notch m⁶ to engage the clutch disengaging device m⁵. The clutch disengaging device m⁵ has a stem m⁷ furnished with a spring m⁸ operating to hold

said device m^5 normally in the annular groove m^4 of the clutch sleeve m^3 . To retract the clutch disengaging device m^5 and permit the clutch pin m^2 to be moved by its spring m^9 into engagement with the clutch member m^1 and the shaft M^1 thus clutched to its operating worm m^{21} , the stem m^7 is furnished with a notch or projection m^{10} adapted to be engaged by a safety trip device P mounted on the operating arm P^1 , which is connected by a link P^2 with the clutch lever h^7 , and which trip device P is furnished with a spring p for holding it in position, and with a pin p^1 having a roller p^2 adapted to engage a stationary cam p^3 on the frame of the machine so that the safety trip device will be automatically disengaged from the stem of the clutch disengaging device m^5 by the operation of the clutch lever through the foot treadle after the clutch disengaging device m^5 has been withdrawn and the stop cam started to revolve, so that the clutch disengaging device can return to its operative position in the groove m^4 of the clutch sleeve m^3 and thus disengage the clutch when the stop cam M has completed its revolution and the seaming operation on the can is finished, and this independent of whether or not the operator keeps the foot lever or treadle E depressed or not.

To enable the cam sleeve H^2 to rotate continuously with the seaming head sleeve when the differential gear h^3 is unclutched from its shaft h^2 and to rotate at the same speed with said seaming head sleeve at such time, while at other times it is free to be rotated at a different or higher speed when said differential gear h^3 is clutched to said shaft h^2 , a movable or pawl connection R R^1 is provided between the seaming head and the cam sleeve H^2 , the same preferably consisting of one or more spring pawls R on one member and one or more slots as R^1 on the other member, the pawls having inclined ends so as to freely permit the cam or cam sleeve to rotate faster than the seaming head, while preventing the same from rotating at a slower speed. This yielding or pawl connection between the seaming head and cam sleeve thus enables the one part to be driven at a slightly different speed from the other, as required, while at the same time causing the two to always rotate continuously, and both rotate at the same speed excepting when the cam sleeve is independently operated intermittently as required by the differential gear h^3 .

The stop cam shaft and the worm and worm gear for driving it, the clutch for connecting and disconnecting the worm gear with said shaft, and the safety trip device thus constitute an automatic stop and start controlling mechanism for connecting and disconnecting the differential gear with the seaming tool operating cams at the beginning of each seaming cycle or period and at the

completion thereof. And as this differential gear controlling mechanism is itself set in operation through link h^{17} by movement of the foot lever or treadle to chuck the can against the upper or stationary chuck, the seaming tools are thus brought into operation the instant the can is properly chucked and disconnected after the seaming head makes the required series or number of revolutions for each seaming cycle or seaming operation on each can. The stop cam and the locking arm on the clutch lever which engages the stop cam serves to insure the stopping of the differential gear controlling mechanism at the proper time independent of the period the operator may keep his foot upon the foot lever or treadle, as the safety trip device causes the clutch disengaging device to be immediately restored to operative position entirely independent of the period the foot lever may be kept depressed. The seaming rollers and seaming roller operating cams on the continuously rotating seaming head are thus always kept in proper registry or position to receive a new can and to discharge or release a seamed one, and no particular skill is therefore required to properly operate the machine.

We claim:

1. In a stationary can double seaming machine, the combination with an upper stationary can holder, of a lower reciprocating can holder, a foot lever for operating it, a continuously rotating seaming head, seaming rollers and seaming roller levers, continuously rotating cams for actuating the seaming rollers, and adapted to be driven at times at a differential speed from the seaming head, and at other times to rotate at the same speed therewith, mechanism for rotating the seaming head, mechanism for differentially rotating said cams at intervals as required for each seaming operation, means operated by said foot lever for setting in operation said cam actuating mechanism, a stop mechanism for said cam operating mechanism, and means for setting said stop mechanism in operation simultaneously with said cam operating mechanism by action of the foot lever so that said stop mechanism will disengage the cam operating mechanism at the completion of each cycle or seaming operation period, substantially as specified.

2. In a stationary can double seaming machine, the combination with a pair of can holder chucks, of a foot lever for reciprocating one of said chucks, of a continuously rotating seaming head, seaming mechanism carried thereby, seaming roller actuating mechanism carried by said seaming head and rotating therewith, mechanism for differentially rotating said seaming roller actuating mechanism, connections for setting said mechanism in operation by movement

of the foot lever and a stop mechanism for automatically disengaging said mechanism which differentially operates the seaming roller actuating mechanism, substantially as 5 specified.

3. In a stationary can double seaming machine, the combination with an upper stationary chuck, of a lower reciprocating can holder chuck, a foot lever for operating it, a continuously rotating seaming head carrying seaming rollers and seaming roller levers, continuously rotating cams for actuating said seaming roller levers, a differential gear for rotating said cams at a differential speed 10 at intervals during each cycle or seaming operation period, a clutch for connecting and disconnecting said differential gear, a clutch lever operated by said foot lever, a locking arm connected with said foot lever, a stop 15 cam mechanism for rotating said stop cam, and means for connecting and disconnecting said stop cam with its operating mechanism at the beginning and end of each cycle or seaming period, substantially as specified.

4. In a stationary can double seaming machine, the combination with an upper stationary chuck, of a lower reciprocating can holder chuck, a foot lever for operating it, a continuously rotating seaming head carrying seaming rollers and seaming roller levers, continuously rotating cams for actuating said seaming roller levers, a differential gear for rotating said cams at a differential speed 20 at intervals during each cycle or seaming operation period, a clutch for connecting and disconnecting said differential gear, a clutch lever operated by said foot lever, a locking arm connected with said foot lever, a stop cam mechanism for rotating said stop cam, and means for connecting and disconnecting said stop cam with its operating mechanism at the beginning and end of each cycle or seaming period, substantially as specified.

5. In a stationary can double seaming machine, the combination with a continuously rotating double seaming head, and seaming tools carried thereby, of a continuously rotating cam for actuating the seaming tools and a movable connection between said seaming head and cam for causing the seaming 30 head and cam to rotate together at intervals, while permitting the cam at intervals to be rotated at a differential speed, substantially as specified.

6. In a seaming machine, the combination with a continuously rotating seaming head, of a continuously rotating cam and a movable connecting pawl between said head and cam, adapting the cam at times to rotate at the same speed with the head and at other

times at a differential speed, substantially as 65 specified.

7. In a stationary can seaming machine, the combination with an upper can holder chuck and a lower reciprocating can holder chuck, of a foot lever for operating the lower chuck, a continuously rotating seaming head carrying seaming mechanism, a continuously rotating cam for operating the seaming mechanism carried by the head, a differential gear for rotating said cam, a clutch for said differential gear, a clutch lever, connections between said clutch lever and said foot lever, an intermittently rotating stop cam mechanism controlling the operation of said clutch by the stop cam and mechanism for 70 starting and stopping said stop cam from the foot lever, substantially as specified.

8. In a stationary can seaming machine, the combination with an upper can holder chuck and a lower reciprocating can holder 85 chuck, of a foot lever for operating the lower chuck, a continuously rotating seaming head carrying seaming mechanism, a continuously rotating cam for operating the seaming mechanism carried by the head, a differential gear for rotating said cam, a clutch for 90 said differential gear, a clutch lever, connections between said clutch lever and said foot lever, an intermittently rotating stop cam, mechanism for intermittently rotating said 95 stop cam, comprising a cam shaft, a worm gear loose on said shaft, a worm for driving said worm gear, a clutch, a clutch disengaging device, a movable trip device for operating the clutch disengaging device, said trip 100 device being carried on an arm connected with said foot lever substantially as specified.

9. In a stationary can seaming machine, the combination with an upper can holder chuck, and a lower reciprocating can holder 105 chuck, of a foot lever for operating the lower chuck, a continuously rotating seaming head carrying seaming mechanism, a continuously rotating cam for operating the seaming mechanism carried by the head, a differential gear for rotating said cam, a clutch for 110 said differential gear, a clutch lever, connections between said clutch lever and said foot lever, an intermittently rotating stop cam, mechanism for intermittently rotating said 115 stop cam comprising a cam shaft a worm gear loose on said shaft, a worm for driving said worm gear, a clutch, a clutch disengaging device, a movable trip device for operating the clutch disengaging device, said trip device being carried on an arm connected with 120 said foot lever, and a stationary projection for releasing the clutch disengaging device from said trip device, substantially as specified.

10. In a stationary can double seaming machine, the combination with a continuously rotating seaming head, seaming rollers

- and seaming roller rock shafts carried by said head, said rock shafts being each furnished with an arm provided with an adjustable member upon which the seaming roller is mounted, said arm and adjustable member having interengaging registering devices, said registering devices on one of said parts being spaced for cans of different diameters substantially as specified.
10. 11. In a stationary can double seaming machine, the combination with a continuously rotating seaming head, seaming rollers and seaming roller rock shafts carried by said head, cams for operating said rock shafts, said rock shafts having operating arms provided with a movable member and an interposed cushion, through which only power is communicated to the seaming roller to cause the same to exert a yielding pressure against the seam, said rock shaft having also a further arm provided with an adjustable member upon which the seaming roller is mounted, said last mentioned arm and said adjustable member having interengaging registering devices, said registering devices on one of said parts being spaced for cans of different diameters substantially as specified.
12. In a stationary can double seaming machine, the combination with a continuously rotating seaming head, and seaming tools carried thereby, of a continuously rotating cam for actuating the seaming tools and a movable connection between said seaming head and cam for causing the seaming head and cam to rotate together at intervals, while permitting the cam at intervals to be rotated at a differential speed, a differential gear for rotating said cam, a clutch 40 for connecting and disconnecting said differential gear with said cam and a stop and start mechanism for controlling the operation of said clutch, substantially as specified.
13. In a stationary can double seaming machine, the combination with a continuously rotating double seaming head, and seaming tools carried thereby, of a continuously rotating cam for actuating the seaming tools and a movable connection between said seaming head and cam for causing the 50 seaming head and cam to rotate together at intervals; while permitting the cam at intervals to be rotated at a differential speed, a differential gear adapted to be connected with said cam for driving it at a differential speed, and a stop and start mechanism for controlling the connection and disconnection of said differential gear with said cam, substantially as specified.
14. In a stationary can double seaming machine, the combination with a continuously rotating double seaming head, and seaming tools carried thereby, of a continuously rotating cam for actuating the seaming tools and a movable connection between 65 said seaming head and cam for causing the seaming head and cam to rotate together at intervals, while permitting the cam at intervals to be rotated at a differential speed, a differential gear adapted to be connected 70 with said cam for driving it at a differential speed and a stop and start mechanism for controlling the connection and disconnection of said differential gear with said cam, an upper can holder chuck, an opposing reciprocating can holder chuck, a foot lever 75 for operating it, and connecting means between said foot lever or treadle and said mechanism for controlling the operation of said differential gear, substantially as specified.
